DESIGN FOR A VELOCIPED

Julius Januszewski, Brooklyn, N. Y.

Application August 21, 1947, Serial No. 140,987

Term of patent 7 years

(CL. D34—15)

To all whom it may concern:

Be it known that I, Julius Januszewski, a citizen of the United States, residing at No. 376a 12th Street, Borough of Brooklyn, in the county of Kings, city, and State of New York, have invented a new, original, and ornamental Design for Velocipedes, of which the following is a specification, reference being had to the accompanying drawing, forming part thereof.

Figure 1 is a perspective view; Figure 2 a side elevation; and Figure 3 a plan view, of a velocipede, showing my new design.

I claim:

The ornamental design for a velocipede, substantially as shown.

JULIUS JANUSZEWSKI.
